DESIGN.

H. HUNT.

CARPET.

No. 15,436.

Patented Oct. 7, 1884.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,436, dated October 7, 1884.

Application filed August 6, 1884. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists in the novel arrangement, which is clearly shown in the photograph, of a figure somewhat resembling a crown having on its front a Greek cross and surmounted by an arch and pendant. 15

I claim—

The design for a carpet, substantially as shown and described. 20

HENRY HUNT.
